COMBINED COMB AND HAIR-LIFTER OR SIMILAR ARTICLE

Arturo Sampedro, 1208 N. Gordon St.,
Hollywood, Calif. 90038

Filed May 20, 1966, Ser. No. 2,364

Term of patent 14 years

(Cl. D86—8)

FIG. 1 is a front perspective view of a combined comb and hair-lifter or similar article showing my new design, the side opposite being plain, unornamented, and without teeth elements; and

FIG. 2 is an enlarged front elevational view thereof shown broken away for convenience of illustration.

I claim:

The ornamental design for a combined comb and hair-lifter or similar article, substantially as shown and described.
